WINDOW SASH FASTENER

Charles L. Casey, Riverside, and Juddson B. Ryno, Chicago, Ill., assignors, by mesne assignments, of one-half to said Charles L. Casey and one-half to Rose E. Casey, both of Riverside, Ill.

Application October 27, 1945, Serial No. 625,004

5 Claims. (Cl. 292—207)

1

This invention relates to improvements in window sash fasteners for locking the sashes together against relative movement, thereby preventing unauthorized opening of the window, as a safety precaution.

To the attainment of these ends and the accomplishment of other new and useful objects as will appear, the invention consists in the features of novelty in substantially the construction, combination and arrangement of the several parts, hereinafter more fully described and claimed, and shown in the accompanying drawing illustrating this invention, in which

Fig. 1 is a sectional view of the adjacent parts of an upper and a lower window sash, having a sash fastener constructed in accordance with the principles of this invention mounted in place and in an operative position.

Fig. 2 is a horizontal sectional view as taken on line 2—2, Fig. 1.

Fig. 3 is a detail perspective view, on an enlarged scale, of the snubber or locking lever.

Fig. 4 is a detail perspective view, on an enlarged scale, of the base plate or supporting member for the locking lever.

Fig. 5 is a detail perspective view of the pivot pin.

Fig. 6 is a side elevation of the fastener, showing the manner in which the pivot pin may be positioned between the base plate and the snubber, to maintain the snubber in an inactive position.

Referring more particularly to the drawing, the numeral 10 designates a base plate or supporting member which is preferably formed as a light sheet metal stamping having a certain degree of resiliency as is common with most stampings of this nature and having upwardly projecting sides 11, and a downwardly projecting portion or flange 12 at one end thereof. This supporting member may be of any desired size and constructed of any suitable material, a longitudinal slot 13 being provided in the plate. Any number of openings 14 may be provided in the sides 11, for a purpose to be later described, and they are preferably in register, respectively, with each other. The upper edges of the sides 11 may be of any desired configuration, but are preferably inclined, as at 15.

A snubber or locking lever 16 is preferably formed with a body portion 17 having downwardly projecting side flanges or portions 18, the body portion 17 terminating short of the ends of the side flanges or portions 18 to form a bifurcated portion 19, and a plurality of aligned open-

2

ings 20 are provided in the ends of the side flanges or portions 18 which form the side walls of the bifurcation 19. The opposite end of the locking lever or snubber 16 is shaped to form an end portion 21 beyond the side flanges or portions 18, and extends in a direction opposite to that of the flanges 18. The extremity of the end portion 21 may be given any desirable shape, but it is preferably shaped to form a curve or rounded extremity 22. A snubber pad 23, such as rubber or any suitable material that will cause a binding action, may be provided, which may be sleeved or otherwise attached or secured to the extremity 22.

15 The snubber or locking lever 16 is attached to the base plate so that the sides 18 will fit over the sides 11, and a pivot pin 24 is passed through registering holes 14 and 20 of the two members, so that the snubber or lever will be pivotally connected to the base member.

20 Adjacent one end of the pivot pin 24, there is a reduced portion 25 which is of a width greater than the combined thickness of the side wall 11 of the base plate and the flange 18 of the snubber or lever 16 through which a portion of the pivot pin passes. The other end of the pivot pin is preferably formed into a U-shaped portion 26, the arm 27 of which is considerably shorter than the body portion of the pin.

25 The fastener is secured to the upper cross rail 28 of the lower sash 29 in a position that the flange 12 of the base plate will engage the outer face of said rail, and is secured in such position by a fastening device, such as a screw 30 that passes through the slot 13 and into the sash rail 28. The slot 13 permits of an adjustment of the fastening screw 30, to accommodate sash rails of different thicknesses. The pivot pin is also inserted into the registering holes in the base plate and snubber, according to the size of the rail 28, so that when the parts are in position, the snubber pad 23 will rest by gravity against one of the upright sides 31 of the upper sash.

30 The extremity 32 of the pivot pin is of such a size as to permit the pin to be entirely withdrawn or detached, so as to permit it to be inserted into other registering openings 14, 20, according to the size of the window to which this device is applied, and also to permit the device to be shipped or stored in a knockdown condition.

35 When the snubbing device is in its operative position, that is, when the arm 27 is removed from its wedging position between the two parts 10 and 16, the arm 27 will rest by gravity on the sash rail 28 and the snubber 16 will rest by

gravity against the upright side 31 to effect a snubbing action whenever an attempt is made to raise the window sash relative to the upper sash, while permitting free movement of the lower sash in the other direction. Since the extent of the reduced portion 25 of the pivot pin 24 is sufficiently great so as to permit a certain freedom of lateral movement between the two main parts of the device, when it is desired to render the device inoperative it is merely necessary for the operator to raise the snubber 16 and also rotate the pivot pin 24 about its axis so as to bring the arm 27 into alignment with the V-shaped crotch existing between adjacent sides of the two parts and thereafter, by forcing the pivot pin in the proper direction, the extreme end of the arm 27 will act as a wedge between the two parts and maintain the snubber in an elevated position, as shown in Fig. 6, so that the buffer pad 23 is clear of the upright sides 31 of the upper sash. In this position of the pivot pin 24 and arm 27 the weight of the snubber 16 resting on the end of the arm 27 will "pinch," so to speak, the arm and prevent lateral displacement thereof.

When the arm 27 of the pivot pin 24 is to be positioned between the adjacent edges of the flanges or sides 18, 11, the lever or snubber 16 may be swung about its pivot, so as to move the buffer 23 out of contact with the window frame 31, by grasping the end 26 of the pin, drawing the same forward and rotating the pin 24 in its bearings to a position that the end 27 may be inserted between the lower edge of the side wall 18 of the snubber and the top edge 15 of the side wall 11, of the base plate 10, by moving the pin backward in its bearings.

While the preferred form of the invention is herein shown and described, it is to be understood that various changes may be made in the details of construction and in the combination and arrangement of the several parts, within the scope of the claims, without departing from the spirit of this invention.

What is claimed as new is:

1. A window sash fastener embodying a base plate having upwardly projecting sides, there being aligned openings in said sides, a snubber having downwardly projecting flanges provided with aligned openings, a pivot pin for swingingly connecting said plate and snubber, means whereby said base plate may be secured to a sash in a position such that a portion of said snubber will engage the other sash, an extension on said pivot pin having an inturned end, said pivot pin being capable of limited axial sliding movement laterally of the base plate and snubber whereby said inturned end may be inserted between the base plate and snubber to prevent movement of the snubber about its pivot in one direction.

2. A window sash fastener embodying a snubber, means pivotally mounting said snubber upon one of the window sashes, said snubber being adapted to engage and wedge against the other sash, when said sashes are relatively moved in one direction, and means adapted to engage said snubber beyond the pivot thereof, for maintaining said snubber out of its locking position, to permit the sashes to be freely and relatively moved in either direction, the last recited means constituting a portion of the first recited means.

3. A window sash fastener for relatively movable sashes including a supporting member adapted to be secured to one of the sashes, a snubber, a pin pivotally connecting the snubber ad-

jacent its end to the supporting member, whereby when the snubber engages the other of the sashes, and said sashes are relatively moved in one direction, the sashes will be locked together, said pin being freely movable axially and relative to said snubber and member, said pin being formed with a reverse bend therein, the extreme end of the reverse bend being capable of entry into the space existing between said snubber and member to maintain the snubber elevated by a wedging action to thus render the same inoperative.

4. A window sash fastener for relatively movable sashes comprising a supporting member adapted to be secured to one of the sashes, a snubber, a pivot pin extending completely through said supporting member and snubber and serving to pivotally connect the snubber to the supporting member whereby an upper surface of the supporting member and a lower surface of the snubber may assume different angular positions relative to each other and whereby said snubber may rest by gravity upon the other sash to prevent relative movement between the sashes in one direction while permitting such relative movement in the other direction, one end of said pivot pin exteriorly of the supporting member and snubber being bent laterally of the pivot pin and having a reversely extending end substantially parallel to the pivot pin, said pivot pin having limited freedom of movement axially and relative to the supporting member and snubber whereby said reversely extending end may enter the space existing between the snubber and supporting member to maintain the snubber elevated and out of contact with said latter sash or be withdrawn from such space to permit free tilting movement of the snubber on said supporting member.

5. A window sash fastener for relatively movable sashes comprising a supporting member adapted to be secured to one of the sashes, said member being substantially U-shaped in cross-section and provided with upstanding parallel sides, a snubber likewise substantially U-shape in cross-section and having downwardly extending parallel sides, there being a series of aligned openings in the sides of said supporting member, there being a series of aligned openings in the sides of said snubber, said openings being arranged in pairs and the openings in the sides of the snubber being designed for selective register with the openings in the sides of the supporting member, a fastening device comprising a member including an elongated pivot pin portion adapted to be passed through the selected registering openings in the sides of said supporting member and in the sides of said snubber to pivotally connect the supporting member and snubber together along a selected transverse axis, said snubber being adapted to rest by gravity against the other sash to effect a snubbing action thereon when one of said sashes is moved relative to the other in one direction only, said pivot pin portion being formed with a reduced portion of an extent in excess of the combined thickness of adjacent sides of the supporting member and snubber, said reduced portion being adapted to be placed in registry with the openings in adjacent sides of the snubber and supporting member to permit limited axial movement of the pivot pin portion and consequently of the fastening device relative to the supporting member and snubber, said fastening device including a lateral extension on said pivot pin exteriorly of the supporting member and snubber and a reversely turned por-

tion at the end of said lateral turned extension, the extreme end of said reversely turned portion being movable from a retracted position wherein it lies wholly outside of the space existing between said snubber and supporting member to an advanced position wherein an end thereof occupies a position between said supporting member and snubber to effect a wedging action between the supporting member and snubber to maintain the latter elevated and out of contact with said latter sash.
